CLAIM

The ornamental design for a vessel wrap, as shown and described.

DESCRIPTION

As an example illustrating the nature and intended use of the article, the vessel wrap may be used for wrapping around a vessel or other hollow receptacle, such as a wine bottle or other bottle, for protecting against over-pour, spillage or drips.

FIG. 1 is a front elevation view of a vessel wrap showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view of the vessel wrap in an alternate, flat position, the rear elevation view being a mirror image, exclusive of the items shown in broken lines; and,

FIG. 8 is a right side elevation view thereof.
